[57] CLAIM

The ornamental design for a heat sink with spring clip, as shown and described.

DESCRIPTION

FIG. 1 is a top, front perspective view of a heat sink with spring clip showing our new design, the electronic device being shown in broken lines for illustrative purposes;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof as seen from the left of FIGS. 1 and 2;

FIG. 7 is a side elevational view thereof as seen from the right of FIGS. 1 and 2.
